UNITED STATES PATENT OFFICE.

LENA E. JARVIS, OF SAN FRANCISCO, CALIFORNIA.

MOUNTING FOR OIL-BURNERS.

1,280,747.

Specification of Letters Patent.

Patented Oct. 8, 1918.

Application filed May 29, 1917. Serial No. 171,653.

To all whom it may concern:

Be it known that I, LENA E. JARVIS, a citizen of the United States, residing in the city and county of San Francisco and State 5 of California, have invented certain new and useful Improvements in Mountings for Oil-Burners, of which the following is a specification.

This invention relates to improvements 10 in rotary spray burners for liquid fuel such as hydrocarbon oils, and more particularly to that type of burner set forth in Patent No. 1,201,828, granted to me October 17, 1916.

The invention has for its principal object 15 to provide an oil burner adapted for suspending on a furnace door or wall plate and which is capable of swinging relatively thereto to admit of accessibility to the tip thereof; to provide an improved swing- 20 ing joint mounting for the burner and associated parts whereby contact is made for supplying current to the motor when the burner is flush with the furnace door and the contact is automatically broken on the re- 25 moval or swinging of the burner from the door; to provide a hinge construction enabling the fuel to be carried through the same and the excess fuel returned to the source of supply thereby eliminating numerous pipe 30 joints and connections.

With the above mentioned and other objects in view, the invention consists in the novel construction and combination of parts hereinafter described, illustrated in the accompanying drawings and pointed out in the claim hereto appended; it being understood 35 that various changes in the form, proportion, size, and minor details of construction within the scope of the claim may be re- 40 sorted to without departing from the spirit or sacrificing any of the advantages of the invention.

To more fully comprehend the invention, reference is directed to the accompanying 45 drawings wherein:

Figure 1 is a view in perspective of the preferred embodiment of my improved apparatus, illustrating the burner swung away from the furnace door or wall plate.

Fig. 2 is an enlarged side elevation of my improved apparatus, illustrating the arrangement of the different parts thereof.

Fig. 3 is a view in top plan of the preferred form of apparatus.

Fig. 4 is a sectional view taken on line 4-4 of Fig. 3.

Fig. 5 is a view in detail of the burner cup.

Fig. 6 is a view in cross section of the electric contact at the hinge support of the 60 burner.

Referring more particularly to the several views of the drawings, wherein like characters of reference designate corresponding parts,—1 indicates a suitable platform or base secured at one end to the rear wall 2 of a fan or blower casing, said platform mounting on its opposite end a motor 3. The wall 2 is provided with a central air inlet 4 in the center of which is positioned a bearing support 5 carried by a web 6. An outlet 7 is 70 provided centrally of the front case wall 8 and over the same is fitted a cup or housing 9. An auxiliary air inlet chamber 10 secured to the front of the fan casing has its front wall 11 provided with an outwardly 75 projecting cone 12 surrounding the cup or housing 9 in spaced relation. This auxiliary air is admitted to promote combustion.

Extending through the bearing support 5 and carried by a bearing 13 is a rotatable 80 shaft 14 carrying on its outer end the cup 15 disposed within the cup or housing 9, with its outer wall in spaced relation to the inner wall of said housing providing a space 85 for the normal air for proper combustion of the fuel.

The cup is formed with a tapering outer wall 16 and fitted within its contracted rear end is a cup shaped support 17, the rear edge of which is secured to the inner surface of 90 said wall 16, and the outer portion of said cup is perforated as at 18 and spaced from the wall 16. On the rotation of the cup the fuel is forced through the perforations 95 therein and passes from the cup at the peripheral edge thereof. The shaft 14 threads, as at 15', into the wall 19 of said support 17. A suitable fan 20 is mounted on the shaft 14 within the fan or blower casing, and is so designed that on the rotation of the shaft 14 the same will draw air 100 through the inlet 4 and force the same under pressure around the cup 15, confining the flame in cup formation. The shaft 14 extends rearwardly through a transmission gear housing 21 and connects with a motor armature shaft 22 through the coupling 23.

Thus it will be apparent that the operation of the motor will rotate the shaft 14, which in turn operates the cup 15 and fan 20. 105 Extending from the housing 21 is a shaft 24 having geared connection with the shaft 110

14 and said shaft coöperates through a coupling 25 with a suitable fuel pump of any well-known type in a casing 26.

Extending from the side wall 11' of the chamber 10 are the hinged butts 27 adapted to lie between coöperating hinge butts extending outwardly from the face of the furnace door or wall plate 29 secured in any suitable manner to the furnace proper (not shown), and provided with the burner receiving opening 29'. Passing through the coöperating hinge butts are suitable hinge pins in the form of pipes 30 and 31, provided at their upper ends with the respective swinging joints 32 and 33, said pipe 30 below its joint 32 being connected to a fuel feed pipe 34 leading to a fuel supply not shown. The pipe 30 above the joint 32 extends to the pump casing 26, and the oil pumped under pressure from said casing passes through the pipe 35 to the cup 15; the pipe passing upwardly in the fan or blower case in advance of the fan 20 and terminating in a goose neck 36 within said cup shaped support 17. A control valve 37 is mounted within the pipe 35 and leading from said pipe intermediate said valve and the pump casing 26 is a pressure relief pipe 38 in which is mounted a relief valve 39, and said pipe communicates with the pipe 31; the excess fluid returning to the supply source (not shown) through the pipe 40.

Surrounding the pipe 38 above the upper coöperating hinge members is an electric contact member comprising the disks 41 and 42 of insulating material received in an inverted cup or protecting member 43, said members being provided in their centers with aligned openings through which said pipe 38 extends.

The disk 41 is held stationary within the pipe 38 by the key or pin 44, and the same carries the contacts 45 with which are connected the leads 46 passing through a conduit 47 in the cover 43 and leading to a suitable source of power. The disk 42 carries contacts 48 from which extend the leads 49 surrounded by the conduit 50 secured at one end to the disk and extending to the motor to which it is secured as at 51, and with which said leads connect. The contacts 45 and 48 are so arranged as to coöperate when the platform or base is swung to a position as in Figs 2 and 3, at which time current is supplied to operate the motor. A suitable spring 52 coiled about the pipe 38 exerts pressure on the disk 41 and maintains the same in tight frictional contact with its operating disk 42.

It is apparent that the construction of the contact members is such as to provide a

switch for controlling the operation of the motor, as the disk 42 swings with the platform 1, and when the platform is at right angles with the door 29 the contacts 45 and 48 are in register causing a flow of current to the motor and permitting the motor to operate to rotate the burner cup, fan and fuel pump.

On the swinging of the burner away from the doors, as in Fig. 1, the engagement between contacts 45 and 48 will be broken and current to the motor will be automatically interrupted, thereby stopping the feed of the fuel to the fire, thus reducing the liability of the operator becoming burned.

If desirable, auxiliary air inlets 53 may be provided in the periphery of the chamber 10, and said inlets are preferably controlled by a damper 54 within said chamber, operated by a handle 55.

A suitable pivotally mounted latch 56 carried by a member 57 on the door 29 is adapted to engage over the rear wall of the chamber 10 and maintains the burner in closed position, with the burner cup thereof extending through the door opening, as in Fig. 4 of the drawings.

By my improved construction it will be apparent that the fuel feed and pressure return pipes from the motor pass through and provide a hinge pin for mounting the burner and associated parts onto the furnace plate or door thus overcoming the numerous joints and pipe connections now universally used for this purpose.

Having thus described my invention, what I claim is:—

An oil burner mounting including a furnace plate or door member provided with a burner opening therein, a platform hinged to one side thereof to swing on a vertical axis and adapted for mounting the burner apparatus including the pump and motor units to enable the same to swing as a unit relative to the opening in said plate or door, a pair of pipes extending from a source of fuel supply and providing hinge pins for said hinge and on which said platform swings, said pipes adapted to carry fuel oil to said burner apparatus and to permit the escape of excess fuel therefrom, and an electric motor control carried by said hinge for conveying current to the motor on said platform.

In testimony whereof I have signed my name to this specification in the presence of two subscribing witnesses.

LENA E. JARVIS.
